(57) **CLAIM**

The ornamental design for a fan, as shown and described.

DESCRIPTION

FIG. 1 is a perspective view of our new design.

FIG. 2 is a front side elevation view thereof.

FIG. 3 is a rear side elevation view thereof.

FIG. 4 is a left side elevation view thereof.

FIG. 5 is a right side elevation view thereof.

FIG. 6 is a top plan view thereof.

FIG. 7 is a bottom plan view thereof.

FIG. 8 is an end view as taken along 8—8 line in FIG. 5, omitting the interior mechanism of a motor.

FIG. 9 is an enlarged cutaway view of the part defined by 9—9 in FIG. 12.

FIG. 10 is an enlarged end view as taken along 10—10 line in FIG. 12.

FIG. 11 is an end view as taken along 11—11 line in FIG. 5, omitting the interior mechanism of a motor; and,

FIG. 12 is reference view of our new design.

An article relating to the subject design is an electric fan. The dashed lines in the drawings indicate environmental or surrounding structures that form no part of the claimed design.

All of the material from the Japanese patent which is essential to the claimed design is included in this application. Any material in the Japanese patent which is not present in application forms no part of the claimed design.
